UNITED STATES PATENT OFFICE.

PARMY H. RYDER AND CHARLES W. MOORE, OF BUCYRUS, OHIO, ASSIGNEES TO
SMOKELESS OIL BURNER COMPANY, A CORPORATION OF OHIO.

OIL BURNER.

Application filed August 2, 1922. Serial No. 579,303.

This application is a continuation in part of our copending application Serial #570,198, filed June 22, 1922.

This invention relates to improvements in oil burners, and has for one of its objects the provision of a burner embodying certain features of construction which by slight modifications may be utilized in burners of the high and low pressure types.

10 Another object of the invention is the provision of a burner in which the quantity of fuel passing therethrough may be regulated independently of the atomizing means.

Another object is the provision of a burner in which the atomizing agent may be controlled independently of the fuel supply.

15 A further object of the invention is the provision of means whereby the steam or atomizing agent may be remotely or semi-20 automatically controlled.

Other objects and advantages of the invention will be apparent as the description proceeds.

For a more detailed description of our invention reference is to be had to the accompanying drawings in which

Figure 1 is a longitudinal section of a high pressure burner embodying the invention;

30 Figure 2 is a cross section, taken on lines II-II, of Figure 1;

Figure 3 is a rear end view of the burner shown in Figure 1;

35 Figure 4 is a longitudinal section of a burner constructed in accordance with the principles of our invention and modified so as to adapt it for use on low pressure systems;

Figure 5 is a cross section, taken on lines 40 V-V, of Figure 4; and

Figure 6 is a rear end view of the burner illustrated in Figure 4.

Like reference characters refer to like parts throughout the several figures.

45 Our invention will first be described with special reference to the burner illustrated in Figures 1 to 3 of the accompanying drawings which comprises a casing 1 having reciprocally mounted therein a piston 2.

50 The interior of the casing is provided with what may be termed a pressure chamber 3 and an atomizing chamber 4, the function of which chambers will hereinafter be more fully described. The piston 2 comprises a

cylindrical body portion provided on its 55 forward end with an enlargement or head having substantially centrally disposed radial openings extending from the axis of the piston into a fuel chamber 5. Extending from the piston head is a hollow stem or 60 shank portion 6 provided at its extremity with an external threaded portion 7. The fuel chamber 5 is formed in the piston head by making a centrally located annular groove therein, thus substantially dividing 65 the head into two sections 8 and 9. The forward end of the piston is provided with an internal thread into which is screwed a tapering nozzle 11 adapted to fit into a corresponding orifice provided in the casing 70 1 adjacent the atomizing chamber 4. The shank portion of the piston 2 is journaled in position by means of a screw-threaded stuffing nut 12. Section 8 of the piston head has a central recess which is threaded to accommodate the threaded end of a needle point valve 13 carried upon the inner end of valve stem 14 which extends through a stuffing nut 15 and is provided with a handle 16. The stuffing nut 15 is carried upon the end 75 of the piston shank 6 by having screw-threaded engagement therewith, and said nut is provided with a wheel 10 which affords means for moving the piston in a forward or rearward direction by virtue of the 80 threads provided upon the shank 7 and stuffing nut 12. The nozzle 11 is provided with a central opening 17 which in conjunction with the centrally disposed radial openings 85 constitutes a passageway to the oil chamber 90 5. The needle valve 13 is disposed to control the passageway from the oil chamber by means of the handle 16.

A port 18 places the pressure chamber 3 and atomizing chamber 4 in communication 95 with each other. The port 18 is controlled by a valve 19, the stem of which is suitably journaled in a stuffing nut 21 and carries at its extremity a handle 22. As shown in Figure 1, by providing the wheel 10 with 100 sprocket teeth adapted to be engaged by a chain 23 having its ends connected to cables 24 which may be carried through suitable pulleys (not shown), the piston 2 may be 105 remotely controlled by effecting its movement backwards or forwards by virtue of the threads provided upon shank 7 engaging with those of the stuffing nut 12. This con-

struction is adapted to remotely control either our high or low pressure type burner. The piston 2 is provided with rings 25 so as to make the chambers of the burner gas tight.

An oil inlet 26 and a steam inlet 27 are provided at the top and bottom portions, respectively, of the casing 1. The oil inlet 26 is immediately over section 8 of the piston head and the steam inlet 27 communicates with the steam pressure chamber 3. It is obvious that as the piston 2 recedes or moves inwardly, the oil inlet is placed in communication with the fuel chamber 5, and the supply of fuel permitted to flow through the passageway 17 of the nozzle 11 may be controlled by a handle 16 of the needle point valve 13. It is also obvious that the steam which may be admitted to the atomizing chamber through the port 18 may be regulated by means of valve 19. By virtue of these adjustments it is possible to manually set the burner so as to employ any desired mixture of oil or other liquid fuel and steam or air during the operation of the burner.

Referring now to the modifications shown in Figure 4 it will be noted that the steam inlet 27 is made much larger inasmuch as this type burner is intended to operate upon low pressure air. For the same reasons the passageway between the pressure chambers 3 and 4 is made larger and is not fully controlled by a valve or the like. The fuel and air supply, respectively, are regulated by setting or adjusting the position of the piston 2 by means of the wheel 10.

With the exceptions just mentioned, the two types of burners herein disclosed are similar in construction and a detailed description of the operation of one will suffice for both.

The operation of the burner shown in Figure 1 may be described as follows. The travel of the piston 2 is limited between a closed position (the one illustrated) to that sufficient to permit the full opening of the oil inlet 26 into the fuel chamber 5 and the atomizing port 23 into the atomizing chamber 4. In starting the burner the piston 2 is adjusted by means of wheel 10 so that the fuel inlet 26 and port 18 are opened any desired distance. Further regulation of the fuel supply may be had by adjusting the valve 13.

The adjustment of the valve 19 is such that a proper amount of steam flows through the port 18 into the atomizing chamber and out through the atomizing orifice so as to give the desired mixture of steam and fuel. With these adjustments for a starting condition the mixture of combustion materials may be remotely controlled or semi-automatically regulated through the operation of wheel 10 by the cables 24 down to a point

where the steam and fuel supply may be completely shut off by the closure of the port 18 and fuel inlet 26.

The above adjustments having been made the fuel and steam are turned on and the burner lighted in any suitable manner as by a pilot light or the like. It frequently happens that after the burner has been lighted it is desirable to change the mixture of the combustion materials. For special uses to which our high pressure burner is adapted it is located in more or less inaccessible places, but by means of the cables 24 the wheels 10 may be remotely adjusted which effects a change in operation of the burner.

While the invention has been described with reference to the special embodiments shown, it is obvious that various changes in detail may be made without departing from the spirit and scope thereof, but all such changes are desired to be regarded as contemplated by the invention as defined in the appended claims.

Where the term steam is used in the specification and appended claims, it is wished to be understood as including air as well, and that as used herein it is interchangeable with the word air.

What is claimed is:

1. An oil burner comprising a casing having a piston longitudinally movable therein, said piston being provided with a fuel chamber circumferentially formed in the head thereof and adapted to divide the piston into two sections, an axial opening formed in said piston head and placed in communication with said fuel chamber by radially disposed apertures, and means for regulating the quantity of fuel ejected from said chamber into said opening.

2. An oil burner comprising a casing having a piston longitudinally movable therein, said piston being provided with a fuel chamber circumferentially formed in the head thereof and adapted to divide the piston into two sections, an axial opening formed in said piston head and placed in communication with said fuel chamber by radially disposed apertures, a valve for regulating the quantity of fuel ejected from said chamber into said opening, said valve being controlled by means external to the casing.

3. An oil burner comprising a casing having a piston longitudinally movable therein, said piston being provided with a fuel chamber circumferentially formed in the head thereof and adapted to divide the piston into two sections, an axial opening formed in said piston head and placed in communication with said fuel chamber by radially disposed apertures, said opening being provided with screw-threads adapted to register with threads formed upon a tapered nozzle and a valve for regulating the quantity of fuel ejected from said nozzle.

4. An oil burner comprising a casing having a piston longitudinally movable therein, said piston being provided with a head having extending therefrom a hollow shank portion, said shank portion being provided with external screw threads and extending through a journal member screwed to the open end of said casing, an axial opening formed in said piston, one end of said opening being threaded to accommodate the

needle point valve having a stem extending through said shank portion, said stem being provided at its extremity with a handle whereby said valve may be opened or closed.

15

In testimony whereof, we have hereunto subscribed our names this 31st day of July, 1922.

PARMLY H. RYDER.
CHAS. W. MOORE.
